UNITED STATES PATENT OFFICE

ROBERT WALTER PHELPS, OF CHICAGO, ILLINOIS, ASSIGNOR TO JULIA KING'S CANDY CORPORATION, OF CHICAGO, ILLINOIS, A CORPORATION OF ILLINOIS

DESIGN FOR A BOX

Application filed September 17, 1930. Serial No. 37,000. Term of patent 7 years.

To all whom it may concern:

Be it known that I, ROBERT WALTER PHELPS, a citizen of the United States, residing at 7047 East End Ave., Chicago, Illinois, have invented a new, original, and ornamental Design for a Box, of which the following is a specification, reference being made to the accompanying drawing, forming part thereof, in which is shown a perspective view of a box of my new design.

The opposite side of the box is plain in appearance.

I claim:

The ornamental design for a box as shown and described.

September 12th, 1930.

ROBERT WALTER PHELPS.
